UNITED STATES PATENT OFFICE.

FLORENCE VAN RENSSELAER, OF SWARTSWOOD, NEW JERSEY.

DESIGN FOR A HAT.

No. 38,016.

Specification for Design.

Patented May 15, 1906.

Application filed March 3, 1906. Serial No. 304,127. Term of patent 7 years.

To all whom it may concern:

Be it known that I, FLORENCE VAN RENSSELAER, a citizen of the United States, and a resident of Swartswood, in the county of Sussex and State of New Jersey, have invented a new, original, and ornamental Design for Hats, of which the following is a specification, reference being had to the accompanying drawing, forming part thereof.

The drawing shows a perspective view of a hat embodying my invention.

What I claim is—

The ornamental design for a hat, as shown.

FLORENCE VAN RENSSELAER.
